(57) **CLAIM**

The ornamental design for a handbag, as shown and described.

DESCRIPTION

FIG. 1 is a front perspective view of a handbag showing my new design;

FIG. 2 is a front view of the handbag shown in FIG. 1;

FIG. 3 is a rear view of the handbag shown in FIG. 1;

FIG. 4 is a left side view of the handbag shown in FIG. 1;

FIG. 5 is a right side view of the handbag shown in FIG. 1; and,

FIG. 6 is a top view of the handbag shown in FIG. 1.

The broken line showing of the closure mechanism, fringe, zipper, zipper pull, is for illustrative purposes only and forms no part of the claimed design.

The dotted lines shown other than those representing the closure mechanism, fringe, zipper, zipper pull, portion of the body of the bag, and leather strap are understood to represent stitching.
